UNITED STATES PATENT OFFICE.

HENRY C. MILLER, OF MILWAUKEE, WISCONSIN.

LOOSE-LEAF BINDER.

1,072,633.

Specification of Letters Patent. Patented Sept. 9, 1913.

Application filed August 6, 1910. Serial No. 575,936.

To all whom it may concern:

Be it known that I, HENRY C. MILLER, a citizen of the United States, and resident of Milwaukee, in the county of Milwaukee and State of Wisconsin, have invented certain new and useful Improvements in Loose-Leaf Binders; and I do hereby declare that the following is a full, clear, and exact description thereof.

10 My invention consists in what is herein particularly set forth with reference to the accompanying drawings and pointed out in the claims of this specification, its object being to provide simple, economical, durable and efficient loose-leaf binders that may be readily assembled or taken apart, each binder being of the type that comprises a pair of united hook-carrying plates in rocking engagement with a spring-plate preferably designed for detachable connection with a back to which a pair of covers are flexibly secured.

Figure 1 of the drawings represents a plan view of one of my improved loose-leaf binders in detachable connection with a back to which a pair of covers are flexibly secured, the united hook-plates of the binder being slid back in the spring-plate of the same; Fig. 2, a vertical longitudinal section view of what is shown in Fig. 1, and Figs. 3 and 4 transverse section views respectively indicated by lines 3—3 and 4—4 in Fig. 2.

Referring by numerals to the drawings, 5 indicates a concavo-convex sheet-metal back, 35 and 6 each of a pair of covers in flexible connection with the back as is usual in the art. Struck up from the back, central of the same at suitable intervals longitudinally thereof, are loops 7 that extend through correspondingly arranged slots in a concavo-convex spring-plate 8, and slip-keys 9, 10, are employed in engagement with said loops to hold said spring-plate in detachable connection with said back. By employing the two 40 slip-keys, one engaging a plurality of back-plate loops and the other a single one of said loops, clearance is obtained for the lever hereinafter specified.

The longitudinal edges of the spring-plate are inturned to provide flanges 11 and the paired hook-carrying plates 12 of the binder are caught under said flanges in rocking engagement with said spring-plate. It is preferable to provide the hook-carrying 50 plates with registering transverse kerfs at suitable intervals and to engage the notches

with angularly bent sheet-metal strips constituting stiff ties 13 upon which said plates have play, but while this is a preferred novel construction and arrangement of parts, the aforesaid plates may be otherwise united. The hooks 14 are soldered or otherwise rigidly connected to the plates 12, those of one plate being V-pointed to engage with V-grooves in those of the other plate, as is common in the art. The hook-carrying plates are under compression in the spring-plate, their downward movement being limited by the engagement of the opposing ends of the hooks, and their upward movement is limited by the ties 13 upon which they have loose play and operate in unison.

Fulcrumed within the confines of the spring-plate 8 permanent therewith and extending at one end beyond said plate is a 75 lever 15 of the first class for which the hook-carrying plates 12, opposing its inner end, are the load. The lever is operated to lift the plates 12, when it is desired to spread the hooks 14 apart, said lever being an important feature of my invention, as thereby the lifting of said plates may be effected by thumb-pressure and the spreading of said hooks facilitated.

The lever herein shown is an angularly 85 bent flat strip provided at one bend thereof with trunnions that are caught between the back 5 and transverse indentations 16 of the spring-plate 8, and said spring-plate is longitudinally slotted intermediate of said indentations to provide clearance for said bend of said lever. The upwardly inclined inner end of the lever opposes the hook-carrying plates 12, and its other end is exposed at an end of the binder where it is suitably elevated, as a result of suitable bending of the flat strip from which said lever is made.

I claim:

1. In a loose-leaf binder, a spring-plate, a pair of hook-carrying plates in rocking engagement with the spring-plate, and angular stiff tie-strips engaging registering transverse play kerfs provided in the hook-carrying plates.

2. In a loose-leaf binder, the combination of a sheet-metal back having loops struck up therefrom at intervals longitudinally thereof, a spring-plate having slots therein through which the back-loops extend, a key 105 slideable on the plate and detachably engaging a plurality of the loops, another key also 110 slideable on said plate in engagement with

but one of said loops, a lever fulcrumed on the spring-plate clear of said keys, and opposing hook-carrying plates in rocking engagement with said spring plate over the inner end of the lever, the outer end of said lever being exposed at an end of the binder. 3. In a loose-leaf binder, the combination of a sheet-metal back having loops struck up therefrom at intervals longitudinally thereof, a spring-plate having slots through which the back-loops extend, a key slidable on the plate and detachably engaging the loops, a lever fulcrumed on the spring-plate

clear of the key, and opposing hook-carrying plates in rocking engagement with said spring plate over the inner end of the lever, the outer end of said lever being exposed at an end of the binder.

In testimony that I claim the foregoing I have hereunto set my hand at Milwaukee in the county of Milwaukee and State of Wisconsin in the presence of two witnesses.

HENRY C. MILLER.
